UNITED STATES PATENT OFFICE.

ALBERT SCHMIDT, OF FLINT, MICHIGAN, ASSIGNEE TO CHAMPION IGNITION COMPANY,
OF FLINT, MICHIGAN, A CORPORATION OF MICHIGAN.

SPARK-PLUG.

1,230,796.

Specification of Letters Patent. Patented June 19, 1917.

Application filed January 11, 1917. Serial No. 141,828.

To all whom it may concern:

Be it known that I, ALBERT SCHMIDT, a citizen of the Republic of France, residing at Flint, in the county of Genesee and State of Michigan, have invented certain new and useful Improvements in Spark-Plugs, of which the following is a specification, reference being had therein to the accompanying drawings.

10 The invention relates to spark-plugs more particularly designed for use in high-speed engines, and it is the object of the invention to obtain a construction that will remain operative under high temperature conditions. To this end the invention comprises the construction as hereinafter set forth.

In the drawings:

Figure 1 is a longitudinal section through the plug;

20 Fig. 2 is a cross-section on line α — α Fig. 1.

A is the metallic casing of the plug, which is provided with a shoulder B . C is an insulator having an enlargement D forming a shoulder E for seating against the shoulder A , a suitable gasket F being placed therebetween. The insulator is held against its seat by any suitable means, but preferably by a flange G bearing against an opposed shoulder on the enlargement D , the joint being formed while the metal is hot.

The difficulty with spark-plugs used with high-speed engines is to dissipate the heat communicated to the exposed portions of the insulator and to the electrode with sufficient rapidity to avoid overheating and pre-ignition. A further difficulty is the danger of breaking of the insulator through the unequal heating of the inner and outer portions thereof. The present construction is therefore designed to overcome these difficulties as follows:

The insulator C , instead of extending to the inner end of the plug, is cut short, and 45 the exposed portion of the insulator is formed by a separate member H of tubular form. Between the members C and H is a space in which is placed a metallic member I , and to insulate this member from the outer casing A an insulation J , preferably of mica, is arranged to bridge and overlap the joint between the insulators C and H . Preferably the member J extends from the shoulder B to the inner end of the casing A ,

as shown. K is the insulated electrode, 55 which passes centrally through the insulator C and is provided with a conical head portion L which engages a correspondingly-formed seat in the metallic member I . Beyond this head L is an inwardly-extending 60 portion M of the electrode, which is preferably of tapering form and is inclosed within the insulator J , its inner end being in proximity to the grounded electrode N . The insulator H is retained in place by a flange O 65 on the casing and serves to protect the metallic member I from the heat of the explosion chamber. It is not essential that this insulator H should be highly dielectric, but it is essential that it should be capable of 70 withstanding high heat and protecting the insulator sleeve I therefrom. P is a clamping nut engaging a threaded portion Q of the electrode and drawing the conical head L against the seat in the member I and holding 75 the latter in contact with the inner end of the insulator C .

With the construction described, when the plug is in operation and subjected to high heat, the heat communicated to the exposed 80 portion of the electrode M is conducted outward into the conical head L , from which it is distributed into the metallic member I . This member serves to rapidly absorb the heat and to dissipate the same through the 85 comparatively thin wall of insulation J and also into the insulator C with which it is in contact. Consequently the electrode M is prevented from heating to the pre-ignition point. The insulator H serves to protect the 90 metallic member I from the heat of the explosion chamber and the heat which is communicated to the exposed face of this insulator is conducted outward, passing through the mica sleeve I and into the casing A , 95 which is cooled by contact with the walls of the water-jacket. Thus overheating of this insulator is prevented. It will be noted that the insulator J is mechanically free from the insulator C , so that it is free to expand and contract without affecting the other. On the other hand, the insulator C forms a gas seal for the plug and also the mechanical support for the electrode.

It is often desirable to remove the electrode for cleaning or for some other reason and this is possible by reason of the fact that it may be separated from the metallic mem-

ber I and the conical head L is restricted in diameter so as to pass through the insulator H.

What I claim as my invention is:

- 5 1. In a spark-plug, the combination with the outer casing, of an insulator mechanically secured and sealed within said outer casing, an electrode mechanically supported and sealed in said insulator, a second insulator 10 independent of said first-mentioned insulator, extending inward therefrom and surrounding the exposed end of the electrode, and a metallic member intermediate said insulators, being protected from heat 15 by the inner insulator and forming a means for dissipating the heat from the electrode.
- 20 2. In a spark-plug, the combination with a metallic casing, of an insulator mechanically secured and sealed therein, a tubular insulator extending inward from said first-mentioned insulator and independently secured within said casing, an insulator sleeve surrounding both of said insulators and overlapping the joint therebetween, a metallic member intermediate said outer and inner insulators, an electrode seated upon said metallic member, extending outward through the outer insulator and mechanically secured thereto, the inner end of said 25 electrode extending through said inner insulator, said electrode normally dissipating its heat through said metallic member and being removable therefrom through said inner insulator.
- 30 3. In a spark-plug, the combination with an outer casing, of an insulator mechanically secured and sealed therein, a tubular

insulator extending inward from said first-mentioned insulator and independently secured within said casing, an insulator sleeve 40 surrounding the outer and inner insulators, bridging and overlapping the gap therebetween, a metallic head in the space between the outer and inner insulators and provided with a tapering seat, and an electrode having a head portion for engagement with said tapering seat and a shank portion passing outward through said outer insulator, the inner end of said electrode extending through said inner insulator and the whole 50 electrode being removable through said inner insulator.

4. A spark-plug, comprising a metallic casing, an insulator mechanically secured and sealed in said casing and terminating 55 short of the inner end thereof, a metallic member at the inner end of said insulator, an electrode seated on said metallic member and passing through said insulator, a tubular insulator member surrounding the 60 inner end of said electrode and protecting said metallic member, said tubular insulator being independently secured within said casing, being highly refractory to the heat of the explosion chamber, and an insulator 65 sleeve surrounding and overlapping the gap between the outer and inner insulators and increasing the electrical insulation of the latter, being protected from the high heat thereby.

In testimony whereof I affix my signature.

ALBERT SCHMIDT.
